UNITED STATES PATENT OFFICE.

ELIZABETH B. FERRIS, OF UTICA, NEW YORK.

LADY'S UNDERGARMENT.

Application filed December 13, 1922. Serial No. 606,747.

To all whom it may concern:

Be it known that I, ELIZABETH B. FERRIS, a citizen of the United States, and a resident of Utica, in the county of Oneida and State of New York, have invented certain new and useful Improvements in Ladies' Undergarments; and I do hereby declare that the following is a full, clear, and exact description thereof, which will enable others skilled in the art to which it appertains to make and use the same, reference being had to the accompanying drawings, and to the reference numerals marked thereon, which form part of this specification.

15 My present invention relates to a lady's undergarment of the brassière type and usually combining the brassière with a vest or union suit.

20 The purpose of my invention is to provide an undergarment of the type described which is of new and improved construction and arrangement and which is also very simple in construction and comfortable and efficient in use.

25 A further purpose is to provide a garment of the class described which provides a brassière formed of a long strip of flexible and relatively elastic material such as knitted material and to have this strip act as a binder strip with its central portion extending across the bust and with its ends extending therebeyond about the back of the body and usually brought around to the front of the waist and there detachably and adjustably 30 connected.

35 A still further purpose is to provide a garment of the sort above mentioned either combined with and attached to a vest or union suit or provided with means for holding the upper edge of the central portion with sufficient security above the bust.

40 Fig. 1 is a plan view of a lady's undergarment embodying my invention in its preferred form, that is with the brassière attached to the upper portion of a vest or union suit.

45 Fig. 2 is a front perspective view of said garment in about the shape it would assume when in use and Fig. 3 is a similar rear perspective view of the same garment.

50 Fig. 4 is a vertical sectional view through the front part of said garment before the brassière has been brought back tight against the bust.

Fig. 5 is a plan view of a modified form of my invention showing the brassière not permanently attached to a vest or union suit but having its own means for holding its top edge up in place over the bust.

Fig. 6 is a perspective view of the garment shown in Fig. 5 about as it would appear in use.

Fig. 7 is a similar front perspective view of a further modified form of my invention being a separate brassière as shown in Fig. 5, but having no straps but rather having separate means for holding the top edge of its central portion to the upper portion of the wearer's vest or union suit.

Referring to the drawings in a more particular description and referring first to the form of the invention shown in Figs. 1 to 4 inclusive, it will be seen that the garment includes a vest or union suit 10 preferably of knitted material having a pair of shoulder straps 11 and a brassière 12. The brassière proper is formed of a relatively long binder strip 13 of about the shape and proportion shown in Fig. 1, that is having a central portion 14 with opposite end portions 15 triangular in form, that is tapering to a smaller size towards the extremities 16 of the strip 13. To the extremities 16 of the said strip are attached tie strings 17 conveniently formed of tape or other strong flat and relatively inelastic material.

The upper edge 18 of the central portion 14 of the brassière is in this form of my invention permanently attached to the upper front edge or upper portion of the vest or union suit 10 as by turning the upper portion of said central portion 14 over the top edge of said vest and sewing the parts together by a row of stitches 19. Conveniently this row of stitches may be located just below the upper edge of the garment and so provide a runway through which the draw string 20 may extend about the entire upper edge of the combined garment with its ends extending out through an opening 21 in the front.

The slanting or tapering end portions 15 have their bottom edges 22 on a line with the bottom edge of the central portion 14 and the tapering formation is produced through the upper edge 23 of said end portions 15 slanting downwardly as indicated in Fig. 1.

The binding strip 12 is formed of flexible material having a considerable elasticity

transversely thereof, that is vertically and a limited amount of elasticity lengthwise, that is horizontally. This result is accomplished preferably and conveniently by forming the 5 said strip of knitted fabric of the desired texture so as to have considerable elasticity transversely and a rather limited amount of elasticity lengthwise of the strip, that is horizontally. With knitted fabric of the 10 ordinary structure this may be conveniently accomplished by cutting the strip 13 lengthwise of the material, that is with the wales of the knitted fabric extending lengthwise of the strip and so horizontally or encircling the wearer. It will be understood, however, that I do not limit my invention to this 15 arrangement as it will be obvious that with some forms of knitted fabric there will be sufficient limitation of the stretch even across the wales of the fabric. The central portion 14 is of sufficient width to extend from above the bust to a line therebelow. In use the wearer will put on the vest or union suit and draw up the draw string 20 to draw in 20 the top edge of the combined garment to the proper extent. As this garment will ordinarily be used with a corset 25 the corset will then be put on and fastened in place. Then the central portion 14 of the brassière 25 will be adjusted over the bust and will be stretched down as far as is necessary to cover the bust and ordinarily with the lower edge 24 of said portion 14 overlapping the top edge of the corset 25 with the said lower edge of the brassière outside of the corset. Then the tapering portions 15 are extended 30 about the body back under the arms, crossed in the back and have their extremities brought around in front more or less at the waist line with said end portions then adjustably connected to each other by tying the tie strings 17 together with a suitable knot 26. As the garment is thus put on and fastened it will be adjusted and drawn back 40 across the bust to the desired extent to function as a brassière. The considerable elasticity of the knitted fabric vertically allows the garment to shape itself to the body to the desired extent while the much more limited elasticity of the fabric lengthwise of the strip 12 operates to hold or support the bust to the desired extent. It will be understood that the top and bottom edges of the brassière are of substantially the same degree of elasticity as the body of said strip; in other words that the hem or binding of 50 said strip is substantially as elastic as the body of the strip in order to avoid the effect of the edges being tight before the body of the strip has been drawn tight enough to perform its function.

In several of the drawings the garment is shown with the lower edge 24 of the central portion 14 spaced slightly above the extremities 16 and the tie strings 17 at the

front. This arrangement and proportion of the garment will be a common one especially with large or well developed people, but it will be understood that according to the size of the person and the relative proportioning of the width of the central portion 14 the lower edge 24 of said portion of the garment may be appreciably lower down so as to be really at the waist line and close to or underneath the tie string 17.

Means may be provided such as a strap 27 of tape attached near the lower edge of the central portion 14 of the garment to hold said lower edge down as by fastening said strap to the draw strings 17 by running said draw strings through the said strap.

It will be noted that this garment differs from the usual brassière in that it has no darts, seams or other such method of fitting. It depends entirely for its efficiency upon the fact that it is made of elastic material and cut upon certain lines.

In the forms of my invention shown in Figs. 5 to 7 the brassière is constructed as a separate garment not permanently attached to a vest or union suit. The construction, proportion and arrangement of this garment corresponds to that of the brassière per se already described. In the construction shown in Figs. 5 and 6 in order to hold the upper edge of the central portion 14 in place above the bust a pair of longer shoulder straps as 11^a are provided extending from the upper corners of the central portion 14 over the shoulders to the upper edge of the corresponding tapering side pieces 15. This garment will be put on over the vest or union suit not shown and will be adjusted as already described for the brassière. It will be noted that this form of garment may be readily used with any form of vest or union suit including a vest or union suit having a high neck either with or without sleeves.

In the form of my invention shown in Fig. 7 the separate brassière is not provided with its own shoulder straps, but rather has means to detachably fasten the upper edge of the central portion 14 to the adjacent portion as the upper front edge of the separate vest or union suit shown in this drawing in dotted lines. Such means for detachably fastening the brassière to the vest or union suit and so holding the brassière up in front may be in the form of clips, snaps, hooks and eyes or even buttons and button holes as found most convenient.

I claim—

In a lady's undergarment the combination of a knitted vest or union suit and a long binder formed of a single flat strip of material, appreciably and uniformly elastic lengthwise, and of greater elasticity laterally, said strip having its upper edge intermediate its ends attached to the front of the vest or union suit above the bust and

being there formed with parallel top and bottom edges and of sufficient width to reach below the bust, the ends of said strip decreasing in width and adapted to reach about the body and having the extremities of said strip adjustably connected at the front, said flat binder being sufficiently non-elastic to support the body but being sufficiently elastic to shape itself somewhat to the body. 10

In witness whereof I have affixed my signature, this 7th day of December 1922.

ELIZABETH B. FERRIS.
